Inventor

UNITED STATES PATENT OFFICE.

JOHN C. WIGMAN, OF GREENBAY, WISCONSIN.

SWITCH-SIGNAL.

No. 807,053.

Specification of Letters Patent.

Patented Dec. 12, 1905.

Application filed April 6, 1905. Serial No. 254,125.

To all whom it may concern:

Be it known that I, JOHN C. WIGMAN, a citizen of the United States, residing at Green-
bay, in the county of Brown and State of
Wisconsin, have invented certain new and
useful Improvements in Switch-Signals, of
which the following is a specification.

My invention relates to signals for indicating
the condition of a switch to approaching
trains or to the operator at the station; and
it consists of an electric circuit-closing device
comprising a spring-actuated lever that is
normally held so that the circuit is broken
when the switch is closed; but when the
switch is open a rod secured to the switch-
point swings the lever against the resilience
of the spring and closes the circuit to any
suitable signal or alarm, which remains set
until the switch is closed again.

20 The construction, operation, and advantages
of my invention will be fully explained
hereinafter and illustrated in the accompa-
nying drawings, in which—

Figure 1 is a plan view showing the casing
inclosing the mechanism of my invention
with its cover removed, so as to disclose the
operative parts of the circuit-closer; Fig. 2,
an end view with the casing broken away,
and Fig. 3 a side view with the casing re-
moved and the operating-rod and its casing
in section.

In the drawings similar reference charac-
ters indicate corresponding parts throughout
the several views.

35 A represents the base of my improved
switch-signal, upon which is mounted a cas-
ing B, made of any suitable material and is
designed to protect its contents from the
weather. Mounted at one end of base A is a
lever C by means of a standard c, being se-
cured to said standard by a screw c'. Said
standard c should be insulated from base A
in any suitable manner. At the opposite
end of base A from standard c is mounted
45 another standard D, and secured to said
standard D are posts E and F, the post E be-
ing insulated from standard D.

G and G' represent set-screws mounted in
posts E and F, between which oscillate the
50 end of lever C.

H represents an expansible coil-spring se-
cured to a post I, mounted on base A and in-

sulated therefrom, the other end of said spring
bearing against lever C to hold said lever nor-
mally out of engagement with screw G. 55

J represents a tube secured in the side of
casing B and in the web of the main track K,
and L a rod mounted in said tube, having one
end bearing against the switch-point M,
while on its other end is an insulator-button 60
N, which bears against lever C.

O represents a suitable signal, such as a
red light, and P a battery to energize said
signal, the circuit from the battery to the sig-
nal being through wire Q to screw c', then 65
through lever C, set-screw G, post E, wire R
to the signal, and by wire S from the signal
back to the battery.

Instead of a light-signal a bell or other de-
vice may be substituted, and it will be un-
derstood that by posting the signal adjacent
to the track it will serve to warn the engineer
of the condition of the switch, or if placed in
the station or switchman's booth it will warn
the operator that the switch is set or fails to 75
operate to open the main-line track.

Having thus described my invention, what
I claim is—

1. A circuit-closer for switch-signals, com-
prising, in combination with the switch-point, 80
a bar secured to said switch-point, a lever
mounted to oscillate in a horizontal plane
and positioned to be struck by said bar, elec-
trical connections with said lever and a con-
tact-post in the path of the oscillation of said 85
lever, and means to normally hold said lever
out of contact with said post, substantially
as shown and described.

2. A circuit-closer for switch-signals, com-
prising in combination with the switch-point, 90
a bar secured to said switch-point, a lever
mounted to oscillate in a horizontal plane
and be struck by said bar, a contact-post ar-
ranged in the path of said lever, a suitable
signal, electrical connections between said 95
signal and the lever and contact-post, and an
expansible coil-spring to normally hold said
lever out of contact with said contact-post,
substantially as shown and described.

3. A circuit-closer for switch-signals com-
prising in combination with the switch-point,
a bar secured to said switch-point, a base
suitably mounted adjacent to the switch, a
lever mounted on said base and adapted to os-

cillate in a horizontal plane, the end of said bar adapted to strike said lever, a standard secured to said base, posts secured to said standard on each side of the end of said lever, set-
5 screws mounted in said posts, a suitable signal and battery for energizing said signal, the lever in circuit with the battery and one of the contact-posts with the signal, and a coil-spring to hold the lever out of engagement

with the set-screw in the last-named contact-post, substantially as shown and described.

In testimony whereof I hereto affix my signature in the presence of two witnesses.

JOHN C. WIGMAN.
